UNITED STATES PATENT OFFICE.

HARRY OGLESBY, OF CHESTER, PENNSYLVANIA.

WINDOW-SHADE ADJUSTER.

1,076,905.

Specification of Letters Patent.

Patented Oct. 28, 1913.

Application filed March 22, 1913. Serial No. 756,166.

To all whom it may concern:

Be it known that I, HARRY OGLESBY, a citizen of the United States, residing at Chester, in the county of Delaware and State of Pennsylvania, have invented certain new and useful Improvements in Window-Shade Adjusters, of which the following is a specification.

This invention relates in general to that class of devices which are designed to let down from the top, roller shades for windows, and particularly to improvements in the window shade adjuster for which I have obtained Letters Patent No. 1,017,452. In that device a rod carrying a shade roller bracket is mounted for vertical adjustment at each side of the window, and if, when lowering or raising the roller and shade by means of these rods, the operator permits one rod to move more than the other at any time, it is possible that the roller at one end may come out of its bearing and drop with the shade, and the object of this invention is to so connect the two bracket carrying rods that they cannot thus drop the shade roller.

To this end, my invention consists in the construction and combination of parts forming a window shade adjuster, hereinafter more fully described, and particularly stated in the claims, reference being had to the accompanying drawings, in which:

Figure I is a front view of a window shade, showing my adjusting device in service. Fig. II is a fragmentary top view on a larger scale, showing the characteristic features of this invention in service.

Numeral 5 represents a rail having side flanges 6, and adapted to be secured to the window casing by means of screws 7. Brackets 8, of any usual form to serve as bearings for the shade roller 20, are provided with flanges 9, to engage and slide upon the rail flanges 6. A rod 10, is rigidly secured to each bracket 8, and is fitted to slide vertically through a lug 11, that is fixed to the rail 5. These rods are thus adapted to slide up and down on the rails 5, and means are

provided for securing them at different points. If one rod were moved up or down two inches or more without moving the other 50 rod, the distance between the bearing brackets would be increased enough to let one end of the roller fall, therefore I provide a crossbar in two sections 12 and 13, one of which is to be rigidly, yet removably, secured to 55 each of the rods 10, by means of binding screws 14. Clips 15, with binding screws 16, are provided to secure the two sections 12 and 13 together at any desired point along the sections, in order that the crossbar may 60 be adjusted in length to locate the brackets as required to fit windows of different widths. When in service, the two sections of the crossbar and the two rods 10, should all be so rigidly bound together that they 65 become practically a unit to slide like a sash in the bearings provided.

I claim.

1. In a window shade adjuster, two rails adapted to be secured to a window frame; 70 two rods, each carrying a shade roller bracket and fitted to slide upon one of the said rails; a crossbar in sections adapted to slide one upon the other; means for securing the two sections together at different points, 75 and means for securing each section rigidly yet removably to one of the said rods.

2. In a window shade adjuster, two rods, each carrying a shade roller bracket; bearings for the rods to slide in; a crossbar comprising two sections adapted to slide one upon the other; means for securing the crossbars together at different points, and means for securing the crossbar to both rods substantially as shown and described, whereby 85 the rods and the crossbar constitute a unit to slide like a sash in bearings.

In testimony whereof I affix my signature in presence of two witnesses.

HARRY OGLESBY.
